UNITED STATES PATENT OFFICE.

HAROLD O. BURGIN, OF PANGUITCH, UTAH.

TANK.

Application filed January 28, 1925. Serial No. 4,839.

To all whom it may concern:

Be it known that I, HAROLD O. BURGIN, a citizen of the United States, residing at Panguitch, in the county of Garfield and State of Utah, have invented new and useful Improvements in Tanks, of which the following is a specification.

This invention relates to improvements in vacuum feed tanks and has for an object 10 the provision of a tank of this character in which the number of parts are materially reduced and their operation simplified, so that the cost of manufacture will be reduced and the life of the tank increased.

15 Another object of the invention is the provision of a vacuum feed tank constructed so that the interior thereof is readily accessible for cleaning and repair.

Another object of the invention is the provision of means for thoroughly screening and filtering the liquid as it passes through 20 the tank.

A further object of the invention is the provision of a feed tank which may be used 25 either as a fuel feed, oil filtering or oil feed tank.

With the above and other objects in view, the invention further includes the following 30 novel features and details of construction, to be hereinafter more fully described, illustrated in the accompanying drawings and pointed out in the appended claims.

In the drawings:—

Figure 1 is a sectional view of a vacuum feed tank constructed in accordance with the 35 invention.

Figure 2 is a section at right angles to Figure 1, parts being shown in elevation.

Figure 3 is a section partly in elevation 40 with the valve in a different position from that illustrated in Figure 1.

Figure 4 is a section on the line 4—4 of Figure 1.

Figure 5 is a similar view on the line 5—5 of Figure 1.

Referring to the drawings in detail wherein like characters of reference denote corresponding parts, the reference character 10 indicates a casing which forms the outer shell of the tank and which contains an inner shell 11, the latter dividing the tank into an upper inlet chamber 12 and a lower discharge chamber 13. The tank is provided with a removable top or cover 14, the latter having an internally threaded flange 15 which engages the outer shell or casing 10,

while the inner shell 11 is provided around its top with an annular flange 16 which is clamped between the upper edge of the casing 10 and the top 14. The top 14 is provided with a bracket 17 by means of which the tank may be secured in place in a manner to permit removal of the casing 10 and the shell 11 so that convenient access may be had to the interior.

The top 14 is provided with an opening which threadedly receives a nipple 18 having a port or passage therethrough so as to provide means for connection with a source of liquid supply, such as the fuel tank of an 70 automobile. The outer shell or casing 10 is also provided with an opening within which is secured a threaded nipple 19 which is adapted to be connected to the carburetor of an engine. The nipple 19 extends upwardly an appreciable distance from the bottom of the outer shell 10 as indicated at 20.

Disposed centrally of the inner shell 11 is a tubular post 21 whose upper end is connected to a threaded nipple 22 through the 80 medium of a plug 23. This plug is provided with a central passage which communicates with the bar of a thimble 22 and cooperates with the latter to provide a suction passage 24. The passage 24 is adapted to be connected to the intake manifold of an engine so as to provide suction for the creation of a vacuum within the inner shell 11. Extending from the passage 24 is a vacuum relief port or passage 25 whose outer end communicates with the space provided between the inner and outer shells 11 and 10 respectively, while the last mentioned shell is provided with a passage or port 26 which is open to the atmosphere.

The passage 24 is provided with oppositely located valve seats 27 and 28, while a valve member 29 is common to both of these seats. This valve member is provided with oppositely disposed stems 30 which extend through openings 31 provided upon opposite sides of the valve seats 27 and 28. In addition to providing for the passage of the stems 30, the openings 31 provide communication between the suction passage 24 and the chamber 12 and between the pressure relief ports 25 and said chamber.

Pivotaly mounted within the plug 23 and extending from opposite sides of said plug are arms 32. These arms have their outer ends connected by members 33 which are provided with sockets 34, the latter receiv-

ing the outer ends of the stems 30. These members 33 are pivotally connected to bails or loops 35 which are in turn pivotally mounted in the outer ends of arms 36. These 5 last mentioned arms extend diametrically from the upper end of a sleeve 37 which is slidingly mounted upon the hollow guide post 21. The outer end of the sleeve 37 is provided with a radially disposed stop 10 flange 38.

Mounted for sliding movement upon the sleeve 37 is a float 39 which is adapted to engage the arms 36 and the flange 38.

Communication between the chambers 12 15 and 13 may be established through a passage 39' which is controlled by a vacuum controlled valve 40.

Located within the chamber 13 is a container or receiving chamber 41. This chamber 20 is located directly beneath the outlet end of the passage 39 and is provided with a plurality of spaced filtering screens 42. These screens are located in the path of liquid passing from the chamber 12 to the 25 chamber 13 and provide for the separation of extraneous matter from the liquid. The chamber 41 is provided with an outlet opening 43 which is spaced upwardly from the bottom of the chamber. Thus liquid entering the chamber 41 will be filtered by the screens 42 and any dirt or sediment passing through these screens will gravitate to the bottom of the chamber 41 while the liquid will pass out through the opening 43. The 30 liquid before passing outward through the discharge port provided in the nipple 19 must first reach the height of the inner end of the extension 20 of the nipple so that further settling will be provided for. Any 35 sediment collecting in the bottom of the chambers 13 and 41 may be readily removed by detaching the tank from the top 14.

During the operation of the engine suction through the passage 24 will draw fuel 45 through the supply tank from the nipple 18, the weight of the float 39 upon the flange 38 holding the valve member 29 upon the seat 28. A vacuum or partial vacuum will thus be formed within the chamber 12 which will 50 act to hold the valve 40 closed. Fluid will thus be collected within the inlet chamber 12 so that the float 39 will rise and engage the arms 36, upward movement of the float 55 lifting the valve member 29 from the seat 38 and causing the said member to engage the seat 27. This change of position of the valve member is assisted by means of springs 44 which connect the pins 45 extending from the members 33, the said springs acting to 60 snap the arms 32 over center and hold the valve in position. Suction will thus be cut off and at the same time vacuum within the chamber 12 will be relieved so that the valve 40 will open and the liquid pass out of the chamber 12 into the chamber 13 through the 65

chamber 41. As the chamber 12 empties the float 39 will descend until it engages the flange 38, the weight of the float pulling the sleeve 39' downward and snapping the arms 32 over center so as to engage the valve 70 member 29 with the seat 28.

A deflecting chute or baffle 46 is located beneath the nipple 18 so that force of the liquid entering the tank will not effect the 75 operation of the valve member 29.

While the invention is shown and described as a fuel feed tank it is capable of various other uses. For example it can be used as a combined oil filter and pump by connecting the nipple 18 with the oil reservoir of the engine and connecting the nipples 19 and 24 respectively with oil distributing means and with the intake manifold of the engine.

The invention is susceptible of various changes in its form, proportions and minor details of construction and the right is herein reserved to make such changes as properly fall within the scope of the appended claims.

Having described the invention what is claimed is:—

1. A vacuum feed tank comprising a casing, means dividing the casing into an inlet chamber and a discharge chamber, a fluid inlet for the inlet chamber, a fluid outlet for the discharge chamber, a vacuum controlled valve providing communication between the inlet and discharge chambers, a guide post within the inlet chamber, a passage extending inwardly from one end of the post and providing a suction passage adapted for communication with a source of suction, a vacuum relief port communicating with the suction passage, spaced valve seats within the suction passage between the outer end of the latter and the vacuum relief port, a valve common to both of said seats, said suction passage having openings provided in its walls upon opposite sides of the valve seats, stems extending from the valve through said openings, spring resisted means engaging the stems to yieldingly hold the valve against movement and float actuated means for actuating the valve.

2. A vacuum feed tank comprising a casing, means dividing the casing into an inlet chamber and a discharge chamber, a fluid inlet for the inlet chamber, a fluid outlet for the discharge chamber, a vacuum controlled valve providing communication between the inlet and discharge chambers, a guide post within the inlet chamber, a passage extending inwardly from one end of the post and providing a suction passage adapted for communication with a source of suction, a vacuum relief port communicating with the suction passage, spaced valve seats within the suction passage between the outer end of the latter and the vacuum relief port, a

valve common to both of said seats, said suction passage having openings provided in its walls upon opposite sides of the valve seats, stems extending from the valve through said openings, spring resisted means engaging the stems to yieldingly hold the valve against movement, arms pivotally secured to the post and operatively associated with the stems, means for yieldingly holding the arms against movement and float actuated means for operating the arms.

3. A vacuum feed tank comprising a casing, means dividing the casing into an inlet chamber and a discharge chamber, a fluid inlet for the inlet chamber, a fluid outlet for the discharge chamber, a vacuum controlled valve providing communication between the inlet and discharge chambers, a guide post within the inlet chamber, a passage extending inwardly from one end of the post and providing a suction passage adapted for communication with a source of suction, a vacuum relief port communicating with the suction passage, spaced valve seats within the suction passage between the outer end of the latter and the vacuum relief port, a valve common to both of said seats, said

suction passage having openings provided in its walls upon opposite sides of the valve seats, stems extending from the valve through said openings, spring resisted means engaging the stems to yieldingly hold the valve against movement, arms pivotally secured to the post and operatively associated with the stems, means for yieldingly holding the arms against movement, a sleeve slidable upon the post, means operatively connecting the sleeve and arms whereby movement of the sleeve will actuate the arms to control the position of the valve and a float slidable upon the sleeve for moving the latter.

4. In a vacuum feed tank, an outlet chamber, a discharge chamber, means to control the passage of liquid from the outlet to the discharge chamber, a receiving chamber within the discharge chamber, means to direct the flow of liquid from the discharge chamber into the receiving chamber and said receiving chamber having an opening therein spaced upwardly from its bottom to provide a discharge port into the outlet chamber.

In testimony whereof I affix my signature.
HAROLD O. BURGIN.
